UNITED STATES PATENT OFFICE

ELIHU D. WATT, OF LA GRANGE, ILLINOIS, ASSIGNOR TO RAYMOND CONCRETE PILE COMPANY, OF NEW YORK, N. Y., A CORPORATION OF NEW JERSEY

APPARATUS FOR FORMING CONCRETE FILES

Application filed August 12, 1930. Serial No. 474,745.

This invention is an improvement on the invention disclosed in Patent No. 1,491,832 entitled "Apparatus for making concrete piles" and issued April 29, 1924, to M. M. Upson, in which was described apparatus comprising a corrugated collapsible core for driving corrugated sheet metal shells.

An object of the present invention is to adapt the apparatus for the driving of concrete instead of sheet metal shells. Another object is to so modify the corrugations of shell and core as to give better results in practice.

Further and other objects and advantages will be apparent from the specification and claims, and from the accompanying drawings which illustrate what is now considered to be the preferred embodiment of the inventions.

Fig. 1 shows a collapsible, non-taper triple-threaded core with driving head.

Fig. 2 is a cross-section of a concrete shell section adapted for use with the core in Fig. 1.

Fig. 3 is a cross-section of a shell comprising several sections, after driving and removal of the core.

Fig. 4 is a cross-section of a stack of shell sections in driving position on the core of Fig. 1.

Fig. 5 is an enlarged view of the upper part of Fig. 4 with the core in section to show details of the mechanism thereof.

Fig. 6 is a view on line 6—6 of Fig. 5.

Fig. 7 is a fragmentary view of a portion of Fig. 6 showing the core collapsed.

Fig. 8 shows a modified form of shell.

Fig. 9 shows the driving core engaged with the shell of Fig. 8.

Referring to the drawings, Fig. 1 shows in expanded form the exterior of a driving core of a kind suitable for the practice of the present invention. It is provided with leaves 20, arranged for inward and outward operation by axial rod 22 through the instrumentality of toggle links 24 (Figs. 5, 6 and 7) in the well known manner when rod 22 is raised or lowered by mechanism in driving head 26.

The surface of the core is covered with corrugations, preferably in the form of com-

paratively fine screw threads 28. The thread shown is a triple thread, but the multiplicity of the threading may be anything desired. The corrugations may even be in the form of parallel rings. A shell section in its preferred form is shown in Fig. 2. It is of concrete 30, covered by a casing of thin steel 32, which projects upwardly beyond concrete 30 so as to overlap the shell section above it when the sections are stacked. The inner surface of concrete 30 is provided with threaded corrugations preferably formed by wire 34 partially embedded in the concrete. This wire is of suitable size to engage the core threads 28 and is arranged as a single thread having the same pitch as the triple thread on the core, so that when the core is expanded into the shell (Fig. 5) only every third thread of the core is engaged by a thread of the shell.

In operation the core is suspended in collapsed condition and the stack of shell sections is assembled end to end thereon. Then the core is expanded into the shell. If the threads of core and shell should not happen to register at once all that is required to bring them to registry is one or two light blows of the hammer on head 26.

The assembly is provided with a driving shoe 36 as in Fig. 4. After the assembly is driven to proper depth the core is collapsed and removed, leaving a hollow shell as in Fig. 3, ready to be filled with plastic concrete to form the monolithic pile.

Instead of forming the shell with threads of reinforcing wire 34 a modification as shown in Fig. 8 may be used in which an inner sheet metal lining 40 is provided, threaded with a single thread 42 of proper form to engage one of the multiple threads of the core, as in Fig. 9. In this modification, threads 42 are of course reinforced by the concrete of the shell lining 36.

It is to be understood that the invention is not limited to the specific embodiment herein illustrated and described but may be used in other ways without departure from its spirit as defined by the following claims.

I claim:—

1. In combination, a metallic shell, a tubu-

lar concrete lining therein, driving projections extending inwardly of the bore of said lining and of a material different from that of the lining to reinforce said lining, and a driving core having corrugations engageable with said projections, together with means to expand and contract said core.

2. The invention set forth in claim 1 in which the distance between projections in the shell is a multiple of the distance between corrugations in the core whereby there are unengaged corrugations on the core between each adjacent pair of engaged corrugations on the core.

3. The invention set forth in claim 1 in which the corrugations on the core are in the form of a multiple screw thread, and the projections in the shell are in the form of a single screw thread of the same pitch as said multiple thread.

4. The invention set forth in claim 1 in which the projections in the shell are formed by wires partially embedded in the concrete of the shell and projecting therefrom.

5. The invention set forth in claim 1 in which the inner surface of the shell is lined with sheet metal and the shell projections are formed in said sheet metal, substantially as described.

30. In testimony whereof I hereto affix my signature.

ELIHU D. WATT.
